UNITED STATES PATENT OFFICE.

AUGUST BUERMANN, OF NEWARK, NEW JERSEY.

DESIGN FOR A PATTERN FOR A SPUR.

SPECIFICATION forming part of Design No. 16,388, dated November 24, 1885.

Application filed May 11, 1885. Serial No. 165,114. Term of patent 14 years.

To all whom it may concern:

Be it known that I, AUGUST BUERMANN, a citizen of the United States, residing at Newark, in the county of Essex and State of New Jersey, have invented and produced a new and original Design for Patterns for Use in Casting Spurs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In said drawings, Figure 1 is a plan of the pattern, and Fig. 2 is a sectional view of the same, taken through line *x*.

The essential feature of the design consists in the configurations and ornamentalations hereinafter set forth and claimed specifically.

In said drawings, *a* is the pattern, the side edges of which are curved, as shown in Fig. 1, the curved outlines coming together as they approach the opposite ends of the pattern.

20 At points near the said ends the outlines diverge, as at *b*, so that the extremities are broadened in plan, as at *c*. The outlines of

the broadened parts may be of any shape or contour. The center perforation, *d*, is angular, as shown. The outer face of the pattern *a* is, 30 at one side of the perforation, ornamented by longitudinal grooves *d d*, which widen toward their centers, as shown. On the opposite side the surface is ornamented by roundels *e e*, which are displayed on said surface in a central longitudinal series, and graduated in size, growing smaller as they approach the extremity of the pattern.

What I claim as new is—

The design for a spur-pattern, the same consisting of a pattern with a wide center and edges converging toward the ends, and near said ends diverging, as at *b*, the ends being broadened, said pattern being ornamented on one side of the center with centrally enlarged 45 or widened grooves, and on the other with graduated roundels, as set forth.

In testimony that I claim the foregoing I have hereunto set my hand this 9th day of May, 1885.

AUGUST BUERMANN.

Witnesses:

CHARLES H. PELL,
FREDK. F. CAMPBELL.
